low side walls extending upwardly therefrom and into which is diverted some of the high temperature gases passing to the underside of the hearth to fluidize the solids.

It has already been pointed out above that when heating of the solids is desired, uniform heating of the material is often an important consideration. In order further to insure uniform heating of all of the solids, the rate at which the solids pass and move over the hearth may be controlled responsive to a condition influenced by the temperature of the heated solids at or adjacent to the region at which the material is discharged from the hearth.

The novel features which I believe to be characteristic of my invention are set forth with particularity in the claims. The invention, both as to organization and method, together with the objects and advantages thereof, will be better understood by reference to the following description taken in connection with the accompanying drawings, of which:

Fig. 1 is a side vertical sectional view of apparatus embodying the invention;

Fig. 2 is a transverse vertical sectional view, taken at line 2—2 of Fig. 1, to illustrate the invention more clearly;

Fig. 3 is an enlarged fragmentary sectional view similar to Fig. 2, to illustrate details of the invention;

Fig. 4 is a fragmentary horizontal sectional view, taken at line 4—4 of Fig. 2;

Fig. 5 is a fragmentary view in elevation of the discharge end of the apparatus of Figs. 1 and 2; and

Fig. 6 is a view more or less diagrammatically showing the combustible fuel supply lines for the apparatus of Figs. 1 and 2 and control provisions therefor.

Referring to the drawings, and especially to Figs. 1 and 2 thereof, I have shown the invention embodied in apparatus in which subdivided material is conveyed with the aid of a gas. More particularly, the apparatus comprises a furnace unit 10 in which a high temperature gas is employed not only to convey the subdivided material but also to effect heating thereof while the material is being conveyed.

The furnace unit 10 comprises a refractory wall structure including spaced apart side walls 11, end walls 12 and a bottom 14 which are disposed within an outer metallic shell 15 which is supported in an elevated position above a foundation 16 by appropriate framework 17. In the space between the side walls 11 and extending lengthwise thereof is provided a perforated elongated hearth 18 upon which the subdivided material is supported and along which such material is adapted to travel from an inlet 19 to a discharge opening 20.

The inlet 19 is formed by a closed inclined chute 21 which extends through an end wall 12 and terminates at its lower end at a region immediately above one end of the hearth 18. The upper end of the chute 21 is fixed to a hopper 22 for the subdivided material. A suitable electrically operable mechanical vibrator 23 of any well known type may be fixed to the upper end of the chute 21 to agitate and vibrate the hopper 22 and chute to prevent clogging and jamming of the subdivided material and insure continuous feeding of the material onto the hearth 18. The discharge opening 20 is formed by an inclined chute 24 which extends downwardly from an end

of the hearth 18 and passes through an opening in the opposite end wall 12.

In the furnace unit 10 being described, heated products of combustion are employed as a gas to convey the subdivided material on the hearth 18. In the instant embodiment, two opposing rows of burners 25 are incorporated in the bottom 14 at opposite sides of a vertical slot or opening 26 therein which is coextensive in length with the elongated hearth 18. The rows of burners 25 are inclined toward one another and arranged to project heated products of combustion into the narrow opening or slot 27 formed between the side walls 11 at their lower ends.

As shown in Fig. 6, a combustible fuel mixture may be delivered to each row of burners 25 from a source of supply through a main conduit 28 and branch conduits 29 and 30 which are connected to manifolds 31 and 32, respectively. The combustible fuel mixture passes from the manifolds 31 and 32 through conduits 33 communicating with the burners 25. Suitable controls, including valves 34 and 35 connected in the conduits just described, may be provided to control the pressure and rate at which the combustible fuel mixture is individually supplied to each burner 25. The burners 25 preferably are of a type capable of producing high temperature products of combustion. By way of example, the burners 25 may be of the kind described and illustrated in Hess Patent No. 2,215,079, granted on September 17, 1940, and, if desired, reference may be had thereto for a detailed description of the burner structure.

In order to deliver gases over a wide temperature range to the underside of the hearth, air or any suitable gas is supplied through the slot 26 which mixes with the products of combustion produced and developed by the burners 25. As best shown in Fig. 2, provision is made for recirculating the spent heated gases and adding fresh air to such recirculated gases.

To this end a suitable roof is provided for the furnace unit 10. For reasons which will be given presently, the roof for the furnace unit 10 in the instant embodiment includes an insulated portion 36 and an uninsulated portion 37 having the side walls thereof spaced apart the same distance as the side walls 12 at the opening at the upper ends thereof. The two roof portions 36 and 37 collectively extend between the end walls 12 of the furnace unit 10. The spent heated gases passing into the roof portion 37 may be discharged therefrom through a conduit 38 directly into the atmosphere, while the spent heating gases passing into the roof portion 36 pass therefrom through a conduit 39 into a separator 40 for separating from the gases any material in a finely divided condition.

The gases stripped of foreign matter pass from the separator 40 through a conduit 41 which is connected to the inlet of a blower 42, the outlet end of which is connected by branch conduits 43 (only one of which is shown in Fig. 2) for discharging the recirculated gases into the spaced apart regions of an elongated hollow metallic shell 44. The shell 44 is fixed to the underside of the refractory bottom 14 and is coextensive in length with the slot or passage 26 which is in communication with the shell. As best shown in Fig. 1, the branch conduits 43 are connected to the shell 44 at regions more or less directly beneath the roof portions 36 and 37.

As shown in Fig. 2, the portion of the conduit 41 adjacent to the bend therein immediately above

the separator 40 is provided with a damper controlled opening 45 for discharging spent gases from the gas recirculation system just described. A second damper controlled opening 46 is also provided in the conduit 41 for adding make-up air. The damper controlled openings 45 and 46 may be of any conventional adjustable type which can be regulated to adjust the proportion of the spent gases discharged from the gas recirculation system and the amount of make-up air mixed with the spent gases.

In this way the temperature of the gases passing through the opening 27 from the region of the burners 25 can be adjusted by regulating the proportion of make-up air added to the recirculated gases which subsequently mix with the high temperature products of combustion at the upper end of the slot or opening 26. It is to be understood that the gases mixed with the products of combustion may be air or any other suitable gas, depending upon the composition of the subdivided material conveyed on the hearth 18 and the nature of the treatment to which the subdivided material is to be subjected, whether chemical and/or physical in character.

In certain instances it may be desirable to dispense with gas recirculation, and, when it is desired to employ especially high temperature gases to act on the subdivided material on the hearth 18, the heating gases may consist entirely of heated products of combustion. In such case, the products of combustion may either be oxidizing or reducing in character or substantially neutral by regulating the proportion of fuel and combustion supporting gas in the combustible fuel mixture supplied to the burners 25, as described in Hess Patent No. 2,215,080, granted on September 17, 1940.

In accordance with the invention, in order to convey subdivided material at a uniform rate on the hearth 18 and thus effect substantially uniform heating of the material by the heating gases passing upwardly through the opening 27, the perforated hearth 18 is provided with a multiplicity of openings distributed throughout all effective regions thereof. Preferably, the hearth 18 is sieve-like in character and such that the heated gases pass therethrough with substantially no reduction in pressure. In the instant embodiment, the sieve-like hearth is obtained by employing screening formed of high temperature alloy material capable of withstanding the high temperature heating gases which pass therethrough.

Immediately beneath the elongated hearth 18 a number of small chambers or cells 47 are provided having partitions 48 therebetween which extend transversely of the hearth. The cells 47 collectively extend from the inlet 19 to the outlet 20 and at the upper ends thereof are in unobstructed communication with the perforated hearth 18. As seen in Figs. 1, 2 and 4, the bottom of each cell 47 is formed with a number of pressure reducing gas apertures 49.

In order to effectively heat the subdivided material on the hearth 18 to the desired high temperature by the heating gases and to reduce heat losses therefrom to a minimum, the side walls 50 of the space 51 immediately above the hearth 18 are hollow, and a portion of the heating gases passing upwardly through the opening 27 into the space 52 beneath the cells 47 is diverted from the latter and passes through the hollow walls. To further reduce heat losses the end wall 12 at

the outlet end of the hearth 18 is formed with dead air spaces, as indicated at 53 in Fig. 1.

In the furnace unit 10 being described, refractory shapes are employed to form the cells 47 and bottom sections of the hollow walls 50 which, in the embodiment illustrated, extend below the hearth 18. The refractory shapes comprise bottom plate portions whose side edges are supported at shoulders formed at the inner surfaces of the side walls 12, as indicated at 54 in Fig. 2. Each refractory shape is formed with an integral upstanding wall section which includes spaced apart parallel walls 55 and a connecting transverse end wall which serves as a partition 48 extending to the inner surfaces of the side walls 11. Hence, each upstanding wall section of a refractory shape forms three walls of a cell unit 47, and, when the refractory shapes are assembled snugly together in abutting relation in the manner shown in Fig. 1, the transverse end of each upstanding wall section closes off the parallel walls 55 of an adjacent wall section to form an independent cell unit.

The walls 55 of the refractory shapes are spaced from the inner surfaces of the furnace side walls 11 to form the lower sections of the hollow walls or passages 50. In addition to the apertures 49 formed therein, the bottom plates of the refractory shapes are formed with openings 56 through which a portion of the heated gases is diverted into the lower ends of the hollow walls 50.

The upper thickened ends of the side walls 55 are formed with recesses to receive the bent sides 57 of the hearth screen. In order to prevent gas leakage at the lateral edges of the hearth screen 18 and between adjacent cells 47, suitable clips 58 formed of high temperature alloy material are inserted in the recesses and wedged against the bent screen sides 57.

At the upper end of the side walls 55 are provided outwardly extending flanges 59. The flanges 59 of adjacent refractory shapes abut one another and collectively form a supporting ledge for a number of hollow refractory tubes 60, as best shown in Figs. 2, 3 and 4. The lower ends of the tubes 60 are open and receive the upper enlarged portions of hollow refractory locating pins 61, the smaller lower portions of which fit into apertures formed in the outwardly extending flanges 59 of the refractory shapes.

The hollow refractory tubes 60 are in abutting relation at each side of the hearth 18 and collectively form the upper sections of the hollow side walls 50 which extend upward from the hearth. The tubes 60 are of such length that they fit snugly between the flanges 59 and notched regions at the upper parts of the side walls 11, as indicated at 62 in Figs. 2 and 3. The extreme upper ends of the tubes 60 are closed to provide a suitable bearing surface at the notched regions 62 and are formed with openings 63 through which the diverted heated gases emerge and mix with the heated gases passing upwardly through the hearth 18 into the space 51.

The furnace unit 10 is divided into two heating zones by suitable partitions. As best shown in Fig. 1, a transverse partition 64 extends downwardly from the juncture of the roof portions 36 and 37 and terminates at the upper ends of the hollow tubes 60. A transverse refractory partition 65 is also provided beneath the cells 47 at a region immediately below the partition 64. The refractory partition 65 is located between the manifolds 31 and 32 at each side of the furnace

unit 10. A partition 66 is also provided in the shell 44 which is directly beneath the refractory partition 65. The partition 66 is provided in the shell 44 in the event it becomes desirable to supply recirculated gases only to the outlet end of the hearth 18 and to supply fresh air to the heating zone at the inlet end of the hearth, as by a suitable blower (not shown), for example.

In order to regulate the temperature of the heating gases supplied to the two heating zones at opposite sides of the partition 65, a suitable control system is provided including a pair of thermocouple members 67 and 68 which extend into the space 52 through a side wall 11, as shown in Fig. 2. The thermocouples 67 and 68 extend into the space 52 at regions at opposite sides of the refractory partition 65. The thermocouples 67 and 68 are connected to suitable potentiometer controls 69 of any well known and conventional type, each of which is connected by conductors 70 to a suitable source of electrical supply. The potentiometer controls 69 are connected to electromagnetically operable valves 71 connected in branch conduits 29 and 30. The valves 71 are of a proportional type and operable to increase and decrease the rate at which combustible fuel mixture is supplied to the burners 25 through the branch conduits 29 and 30 when the temperature of the heating gases in the space 52 tends to fall and rise, respectively, from a predetermined or definite value.

In order further to insure uniform heating of the subdivided material, a suitable control is provided for regulating the rate at which the material is conveyed on the hearth 18. As best shown in Figs. 1 and 5, this is accomplished in the instant embodiment by providing a vertically movable gate 72 for the chute 24 which is raised and lowered at the discharge opening or outlet 20 responsive to a thermocouple member 73 arranged to extend through the end wall 12 at such a height that the inner end thereof is contacted by the heated subdivided material about to pass from the hearth 18 into the discharge outlet 20.

As shown in Fig. 5, the gate 72 is connected through a lever system to a control member 74 of a diaphragm operated device 75 which is operatively associated with any well known control equipment 76 like that known in the trade as a valve positioner. The control equipment 76 is connected in an air supply line 77, and the pressure at which air is supplied thereto is regulated by an electromagnetically operable valve 78 of the proportional type. The valve 78 is regulated by a suitable electronic control 79 of any well known type which is connected by conduits 80 to a source of electrical supply and to which the thermocouple member 73 is also connected.

It will now be understood that when the temperature of the subdivided material about to pass into the discharge opening 20 tends to change from a definite value, the electronic control 79 responds to thermocouple member 73 and causes the valve 78 to vary the pressure of the air supplied to the control equipment 76. The control equipment 76 responds to such variations in air pressure to move the control member 74 of the diaphragm operated device 75 which in turn moves the gate 72 at the discharge opening 20. When the temperature of the subdivided material about to pass into the discharge opening 20 tends to rise above a definite value, the control system just described acts to raise the gate 72; and

conversely, when the temperature of such subdivided material tends to fall from the definite value, the control system acts to lower the gate 72.

In placing the material conveying apparatus just described in operation, solids of relatively small size or in subdivided form are supplied to the hopper 22 and flow therefrom by gravity through the chute 21 onto the hearth 18 at the inlet end thereof. The chute 21 at its lower end is as wide as the distance between the hollow side walls 50. As previously explained, clogging of material in the hopper and inlet chute is avoided by providing the vibrator 23.

The height or depth of the bed of material on the hearth 18, at the region thereof adjacent to the inlet opening 19, is dependent upon the position of the lower edge of a feed gate 81 which is removably secured at its upper end at 82 to the chute 21. For different materials and different rates at which it is desired to move the materials on the hearth 18, a feed gate 81 of appropriate size can be selected to give the desired depth of the bed of material at the inlet end of the hearth.

The depth of the bed of material on the hearth 18 at the outlet or discharge end thereof is always less than that maintained at the feed gate 81 and is dependent upon the position of the outlet gate 72 in the discharge opening 20. Thus, a head of material is maintained between the inlet 19 and discharge opening 20 to effect movement of the material in the desired direction. The chute 21 at its upper end also is as wide as the hearth 18, that is, the distance between the hollow side walls 50.

The gas is supplied under pressure into the space 52 immediately beneath the cells 47. The gas passes into the cells 47 through the pressure reducing gas apertures 49. The apertures 49 are of such size that the velocity pressure of the gas entering the cells is substantially converted to static pressure by the time the gas reaches the underside of the perforated hearth 18. Stated another way, the jet effect of the gas produced at the apertures 49 is sufficiently dissipated in the upper parts of the cells 47, so that the gas will pass through the perforated hearth 18 without subjecting the material therein to any pronounced localized jet effect.

As previously explained, the perforated hearth 18 is sieve-like in character and the gas passes therethrough with substantially no reduction in pressure. The distribution of the gas is more or less uniform over the entire effective area of the hearth and flows through the interstices of the solids to aerate and effect bubbling thereof. The gas is supplied to the underside of the hearth 18 at an adequate rate to maintain the material in what may be referred to as a condition of fluidity, in which condition the material is agitated and bubbling thereof takes place and at the same time a general horizontal movement is imparted to the material which is in the direction toward the outlet 20 due to the head of material between the inlet 19 and discharge opening 20.

By providing a number of cells 47, the gas in space 52 in effect is broken up into a number of streams each of which is effective to act upon a part of the bed of material. In addition, the cells 47 and apertures 49 therefor are so proportioned and of such size that a pressure reduction of the gas in each stream is effected at the apertures 49, and the gas in each cell at a reduced pressure is uniformly distributed over a portion of the under side of the bed of material to fluidize the

latter without subjecting the material to any objectionable or undesirable localized jet effect on account of the pressure velocity of the gas entering the cells.

In this way, uniform and steady flow or movement of the material on the hearth 18 is promoted without any danger of clogging occurring or by-passing of gas through a void in the bed of material. Hence, all regions of the bed of material are more or less substantially in the same fluid-like condition and the movement imparted to the material is generally uniform along all parts of the path of movement provided by the hearth 18 from the inlet 19 to the discharge opening 20, so that piling of the material at any particular region is avoided and the normal average depth of the bed of material is continuously maintained at each particular region of the hearth.

An important advantage gained by use of apparatus like that shown and just described is that the static pressure of the gas in any particular cell 47 will automatically vary independently of the static pressure of the gas in the other cells, when the average depth of the portion of the bed of material immediately above it tends to increase or decrease from its normal average depth. When the average depth of a portion of the bed of material tends to increase above its normal average depth, the static pressure in the cell or cells 47 immediately beneath such bed portion automatically increases to overcome this condition. Conversely, when the average depth of a portion of the bed of material tends to decrease below its normal average depth, the static pressure in the cell or cells 47 immediately beneath such bed portion automatically decreases to overcome this condition.

This automatic increase or decrease in static pressure of the gas in the one or more cells 47 affected is due, of course, to change in resistance to gas flow resulting from the slight variation in average depth of the bed at a particular portion thereof. The static pressure in the cells 47 can vary over a pressure range up to a maximum value substantially corresponding to the static pressure of the gas in the space 52 at the inlet side of the apertures 49. It is desirable to adjust the maximum depth at which the bed of material is maintained at the inlet end 19 of the hearth 18 with respect to the maximum static pressure that can be developed in the cells 47. By maintaining the maximum depth of the bed of material at the inlet end of the hearth such that it can be effectively fluidized and aerated when the static pressure developed in the cells is somewhat less than the maximum value just referred to, the bed of material throughout the length of the hearth will always be maintained in a condition of fluidity and insure a general uniform horizontal movement of the material toward the discharge opening 20.

Among the factors to be considered, in order to maintain an adequate flow rate of gas through the bed of material and insure substantially complete conversion of the velocity pressure of the gas to static pressure, are the number and size of the apertures 49 and the height of the cells 47. In the instant embodiment, a number of apertures 49 are provided at the bottom of each cell 47 whose aggregate cross-sectional area is such that an adequate flow rate of the gas will be obtained. Further, the apertures 49 preferably are of such size that gas is supplied to the underside of the bed of material on the

hearth 18 in a manner characterized by the absence of any objectionable jet effect at localized regions of the hearth.

When fewer gas apertures 49 are employed, experience has shown that the height of the cells 47 must be increased. While a single aperture 49 of appropriate size may be employed for each cell 47, the height of the cells becomes unduly great. Hence, it is preferable to employ a multiplicity of apertures 49 of appropriate size and provide cells 47 of sufficient height to accomplish the desired end result.

Additional factors to be considered to obtain the desired flow rate of gas supplied to the underside of the hearth 18, for example, are the density of the material involved, the size of the particles of material and the depth of the bed of material to be maintained on the hearth. In each instance, the parts of the apparatus of the invention can be properly proportioned, taking into consideration the above factors, to cause movement of material along the hearth in the manner just described.

In the embodiment of the invention shown, the gases are immediately withdrawn from the hearth space 51 through the roof portions 36 and 37 after passing through the bed of material on the hearth 18. When a gas recirculation system is employed like that shown in Fig. 2, it is desirable to maintain the pressure in the hearth space 51, immediately above the bed of material, substantially at atmospheric pressure.

In order to reduce heat losses and avoid objectionable cooling of the particles of material when such particles contact the side walls 50, such side walls are preferably hollow, as previously described. A part of the gas in the space 52 beneath the cells 47 is diverted and passes through the opening 56 into the hollow side walls 50. In passing through the hollow walls 50 the heated gases are subdivided into a plurality of streams in the vertical channels formed by the partitions 48 and walls 55 of the refractory shapes.

At about the level of the hearth 18 the heated gases in the hollow side walls pass through the openings in the locating pins 61 into the hollow tubes 60. The heated gases in passing through the hollow tubes 60 heat the inner surfaces thereof and consequently reduce the temperature differential at the inner and outer surfaces of the inside parts of the tubes which form the inner refractory lining for the hearth space 51. In this way, the particles of material will not be initially heated by the heating gases supplied to the underside of the hearth 18 and subsequently come in contact with a cooler surface. In certain instances, even the slight cooling of particles coming in contact with the cooler side walls adversely affects the uniform heating of the material and results in a non-uniform end product. By maintaining the opposite surfaces of the inner refractory lining of the hearth space 51 at approximately the same temperature, the particles of material moving along the hearth 18 cannot come in contact with low temperature surfaces tending to disturb the uniform heating of the particles of material.

By providing the thermocouple members 67 and 68 in the space 52 which are operatively associated with the electromagnetically operable valves 71, as shown in Fig. 6 and previously described, the temperature of the gas supplied to the hearth 18 can be accurately controlled to maintain the gas at a desired elevated tempera-

11

ture. When the gas in space 52 tends to increase or decrease from the desired elevated temperature, the electromagnetically operable valves 11 respond to the action of the thermocouple members 61 and 62 to reduce or increase, respectively, the rate at which the combustible fuel mixture is delivered through the branch conduits 29 and 30 to the burners 25.

By providing the thermocouple member 13 at the outlet end of the hearth 18 which is operatively associated with the control system in Fig. 5 and previously described, a control is provided to insure that the material about to leave the hearth 18 and pass into the discharge opening 20 is always at the same elevated temperature. When the temperature of the material about to pass into the discharge opening 20 tends to decrease and increase from the desired elevated temperature, the discharge gate 12 responds to the action of the thermocouple member 13 and moves downwardly and upwardly, respectively, to vary the effective size of the discharge opening 20.

When the outlet gate 12 moves downwardly, the rate at which the material leaves the hearth 18 through the discharge opening 20 is reduced, thereby increasing the depth of the bed of material at the vicinity at the inner end of the thermocouple member 13. This reduces the head of material maintained between the inlet 19 and outlet 20 to reduce the rate at which material is conveyed on the hearth. Conversely, when the gate 12 moves upwardly, the rate at which the material leaves the hearth through the discharge opening 20 increases, thereby reducing the depth of the bed of material at the vicinity of the inner end of the thermocouple member 13. This increases the head of material maintained between the inlet 19 and outlet 20 to increase the rate at which the material is conveyed on the hearth 18.

The apparatus of the invention is suitable for use with a variety of materials or solids of relatively small size or in subdivided form. As previously stated, the gas employed to fluidize the material may simply effect movement thereof without reacting physically or chemically with the material. However, the furnace unit 10 illustrated in the drawings and described above is particularly adapted for use with a heating gas which reacts chemically and/or physically with the solids to effect the desired treatment thereof while movement of the material is being promoted by the gas.

By way of example and without limitation, the furnace unit 10 may effectively be employed for roasting coffee, cocoa beans, peanuts, cereals and similar products, to effect the reduction of metallic ores, and for heating refractory balls or pebbles to an elevated temperature for immediate use as a catalyst in the catalytic cracking of hydrocarbon oil.

The furnace 10 is particularly suited for heating subdivided material which requires heating in several heating stages. One example of a material requiring heating in two heating steps is raw glass batch which is in the form of relatively small granules which contain considerable free and combined water. It is extremely desirable to remove both free and combined water from raw glass batch granules because the presence of water in the melting tank causes foaming and results in imperfections, such as beading, for example, in the glass produced.

When the furnace unit 10 is employed for heat

75

12

treating wet raw glass batch granules, the wet granules are delivered to the inlet end of the hearth 18. In the initial heating zone below the roof portion 37, the high temperature heating gases are employed to drive off free water. When substantially all of the free water is vaporized, the granules move into the second heating zone beneath the roof portion 36 in which calcining is effected, that is, combined water is removed from the raw glass batch granules. Since substantial quantities of free water are usually removed from the granules in the initial heating zone, the spent gases containing the moisture are preferably discharged from the roof portion 37 through the conduit 38 directly into the atmosphere. On the other hand, the quantity of combined water removed from the granules in the second heating zone is such that in many instances the spent gases can be recirculated in the manner shown in Fig. 2. In order to effectively segregate the spent gases in the two heating zones, the partition 64 is provided between the roof portions 36 and 37.

The partitions 65 and 66 in the heating space 52 and shell 44 are provided so that gas may be supplied at different volumetric rates to the heating zones when this becomes necessary. This is particularly true when the furnace unit 10 is employed to heat treat raw glass batch granules in which the first heating zone requires heating gas to be supplied thereto at a higher volume rate than in the second heating zone. This is so because the heated gas, which is supplied to the first heating zone to maintain the wet granules in a condition of fluidity, is contracted to such an extent that an excess or additional quantity of heated gas must be supplied to the underside of the hearth to maintain the granules in the desired condition of fluidity. In other words, heated gas at a smaller volume rate is required in the second heating zone beneath the roof portion 36 to remove combined water and maintain the granules therein in the same condition of fluidity as the wet granules containing free water and in the first heating zone beneath the roof portion 37.

In such case, a separate blower may be connected to supply air to the part of the shell 44 beneath the roof portion 37 and at one side of the partition 66. Likewise, since the volume rate at which heated gas is supplied to the heating zone beneath the roof portion 37 is greater than that at which the gas is supplied to the heating zone beneath the roof portion 36, separate manifolds 31 and 32 are provided for the burners 25 in each of the zones and the supply of combustible gas mixture is independently controlled for the two heating zones by the thermocouple members 67 and 68 in the space 52 at opposite sides of the partition 65.

In view of the foregoing, it will now be understood that I have provided an improved apparatus for conveying solids of relatively small size or in subdivided form by maintaining the solids in a fluid condition with the aid of a gas. Although I have shown a single embodiment of my improved apparatus in which burners are provided to heat the gas to an elevated temperature, I do not wish to be limited to the particular arrangement set forth. Thus, in certain instances a cool gas at a relatively low temperature may be employed instead of a heated gas to convey the material along the hearth; and a suitable refrigeration system may be embodied in the apparatus to effect cooling of air to a

13

sufficiently low temperature to freeze the individual solids or particles of material when this is desirable and becomes necessary. I therefore intend in the following claims to cover all modifications which do not depart from the spirit and scope of the invention.

What is claimed is:

1. Apparatus for heating subdivided material and the like comprising structure providing an elongated perforated hearth and spaced apart hollow side walls at opposite sides thereof, and means for supplying heated gas to said hollow side walls for flow therethrough and for supplying heated gas directly from the same source and at the same temperature to the underside of said hearth for flow therethrough to effect heating of the material and at the same time maintain the latter in a condition of fluidity to cause flow thereof along the hearth.

2. Apparatus for heating subdivided material and the like comprising structure providing an elongated perforated hearth and spaced apart hollow side walls at opposite sides thereof and including a chamber communicating with said side walls and the lower part of said hearth, and means for supplying heated gas through said chamber to said hollow side walls for vertical flow therethrough and for supplying heated gas from the same source to the underside of the hearth for flow therethrough to effect heating of the material and at the same time maintain the latter in a condition of fluidity to cause flow thereof along the hearth.

3. Apparatus for heating subdivided material and the like comprising structure providing an elongated perforated hearth and spaced apart hollow side walls at opposite sides thereof, a plurality of burners and means for supplying heated gas directly from the burners to the underside of the hearth for flow therethrough to effect heating of the material and at the same time maintain the latter in a condition of fluidity to cause flow thereof along the hearth, said means being connected with said side walls so that a portion of the heated gas supplied to the underside of said hearth is diverted and passes upwardly through the hollow side walls.

4. Apparatus to effect a change in temperature of subdivided material and the like comprising a perforated hearth, means for supplying gas at a desired temperature to the underside of the hearth for flow therethrough to effect a change in temperature of the material and at the same time cause movement thereof along the hearth, and means responsive to a condition influenced by the temperature of the material for controlling the rate of movement thereof on the hearth.

5. Apparatus to effect a change in temperature of subdivided material and the like comprising a perforated hearth, means for supplying a gas at a desired temperature to the underside of the hearth for flow therethrough to effect a change in temperature of the material and at the same time cause movement thereof along the hearth, and means including a thermal responsive element arranged to be contacted by material on the hearth for controlling the rate of movement thereof on the hearth.

6. Apparatus to effect a change in temperature of subdivided material and the like comprising a perforated hearth, means for supplying gas at a desired temperature to the underside of the hearth for flow therethrough to effect a change in temperature of the material and at the same

14

time maintain the latter in a condition of fluidity to cause movement thereof, control means including a movable member at the discharge end of the hearth for controlling the depth of the bed of material, and means responsive to a condition influenced by the temperature of the material for regulating said control means.

7. Apparatus to effect a change in temperature of subdivided material and the like comprising a perforated hearth, structure to provide gas, control means to control the temperature at which the gas is provided by said structure, means to supply the gas to the underside of the hearth for flow therethrough to effect a change in temperature of the material and at the same time maintain the latter in a condition of fluidity to cause movement thereof, means responsive to the temperature of the gas supplied to the underside of the hearth for regulating said control means, and means responsive to a condition influenced by the temperature of the material for controlling the rate of movement thereof on the hearth.

8. Apparatus for heating solids of relatively small size or in subdivided form comprising means providing a perforated hearth, means for supplying gas at an elevated temperature to the underside of the hearth for flow therethrough to heat the solids and at the same time effect bubbling thereof to cause movement of the solids along the hearth, and means responsive to the temperature of the solids about to pass from the hearth at the discharge end thereof for controlling the rate at which the solids are discharged from the hearth.

9. Apparatus for heating solids of relatively small size or in subdivided form comprising structure providing a refractory lined chamber, means including screening of high temperature alloy material providing an elongated hearth disposed between the opposing side walls of said chamber, means including spaced partitions providing a series of cells at the underside of said hearth in unobstructed communication therewith, said partitions being disposed transversely of the elongated hearth and extending between said opposing side walls, said cells at the bottoms thereof having pressure reducing gas apertures extending therethrough, said structure also providing an unobstructed refractory lined space beneath said cells extending the length of said hearth, and means including burners for producing gas at an elevated temperature and supplying such gas to said space.

10. Apparatus as set forth in claim 9 in which said opposing side walls are hollow and a part of the gas supplied to said space passes through said side walls.

11. Apparatus as set forth in claim 9 in which said burners are embodied in said structure at a refractory lined region thereof communicating with said space, and means for recirculating gas from the space above said hearth to said region.

12. Apparatus as set forth in claim 9 in which said burners are embodied in said structure at a refractory lined region thereof communicating with said space, and structure including conduit means and a blower connected therein for recirculating gas from the space above said hearth to said region, said conduit means having damper controlled openings for discharging spent gases and for introducing make-up air.

13. Apparatus to effect a substantial change in temperature of solids of relatively small size or in subdivided form comprising structure pro-

viding an elongated perforated hearth and spaced apart hollow side walls at opposite sides thereof, means to supply gas to the underside of the hearth for flow therethrough to effect the desired change in temperature of the solids and at the same time maintain the latter in a condition of fluidity to cause movement thereof along the hearth, and means for supplying to the hollow side walls for flow therethrough a gas in the same temperature range as the gas supplied to the underside of the hearth.

14. Apparatus to effect a substantial change in temperature of solids of relatively small size or in subdivided form comprising structure providing an elongated perforated hearth and spaced apart side walls at opposite sides thereof, and means to supply gas to the underside of the hearth for flow therethrough to effect the desired change in temperature of the solids and at the same time maintain the latter in a condition of fluidity to cause movement thereof along the hearth, said means being formed and arranged so that a portion of the gas supplied to the underside of said hearth is diverted and passes upwardly through the hollow side walls.

15. Apparatus for heating subdivided material including in combination an elongated perforated hearth, means supporting said hearth throughout its length including structure forming a plurality of individual cells, means forming a plurality of passages extending along each side of said hearth, structure located below said cells and passages forming a continuous supply path leading to each cell and passage, means simultaneously to force air through said cells and hearth, and through said passages, and burner means located adjacent to said supply path to introduce hot products of combustion into said air.

16. In apparatus for heating subdivided material the combination of a furnace having an elongated chamber therein, the lower portion of said chamber being constricted to form a centrally disposed slot extending the length of said chamber, means forming a plurality of passages lining the sides of said chamber, an elongated perforated hearth upon which the material to be heated is placed, means to mount said hearth in said chamber near the lower ends of said passages, and means to force air through said slot and through said hearth and passages.

17. The combination of claim 16 including burner means located adjacent to and in communication with said slot whereby products of combustion may be discharged into the air flowing through said slot.

18. In apparatus for heating subdivided material the combination of a furnace having an elongated chamber therein, the lower portion of said chamber being formed to provide an elongated air inlet, flue means at the top of said chamber through which air may be withdrawn, an elongated perforated hearth, means to mount said hearth in said chamber to divide the same into an upper and a lower space, the material to be heated resting on said hearth in said upper space, means forming a plurality of compartments in said lower space throughout the length of said hearth, each compartment being in open com-

munication with the lower side of the hearth, the lower ends of each compartment being formed with pressure reducing openings, means to force air through said inlet, compartments and hearth to said flue, and means to heat said air.

19. The combination of claim 18 in which the means to heat the air comprises a plurality of burners located adjacent to said inlet and in communication therewith, whereby products of combustion from the burners heats the air forced through the inlet.

20. In apparatus to heat subdivided material the combination of furnace structure forming an elongated chamber, the lower portion of said chamber being constricted to form an elongated air inlet slot extending substantially the length of said chamber, a flue at the top of said chamber, a perforated hearth, means to mount said hearth in said chamber to divide the same into an upper space into which the material to be heated is placed and into a lower space, burners located in said structure adjacent to said slot and in communication therewith to discharge products of combustion into said slot, and means to force air through said slot into said lower space, from which it passes through said hearth and the material thereon to the flue.

21. The combination of claim 20 including means forming a plurality of compartments or cells in said lower space, each compartment being in direct communication with a portion of said hearth and each compartment being provided in its lower end with pressure reducing openings through which the air flows to the compartments.

22. The combination of claim 21 including means forming a plurality of passages in said chamber on each side of said hearth and extending above the same, said means being provided with openings at the lower end thereof communicating with said lower space whereby air will flow through said openings and passages as well as through said hearth.

23. The combination of claim 20 including means in said chamber forming a plurality of passages on each side of said hearth and which is contacted by the material on said hearth, said means being provided with openings below the hearth to connect said passages and lower space whereby the air may flow through said passages as well as through said hearth.

JAMES B. HENWOOD.
